Nathaniel Baldwin, INVENTOR

UNITED STATES PATENT OFFICE.

NATHANIEL BALDWIN, OF EAST MILL CREEK, UTAH.

TELEPHONE RECEIVER.

Application filed October 31, 1925. Serial No. 66,037.

The present invention appertains to telephone receivers and embodies a general principle disclosed in my former patent No. 957,403 issued May 10th, 1910, namely, the principle of using an armature surrounded by an actuating coil or coils and acted upon at its ends by four polepiece limbs.

The principal object of the present invention is to provide a fulcrum for the armature without the spool in such form that the armature will operate as if the fulcrum were within the spool; or in other words, to provide a virtual fulcrum for the armature within the spool.

I attain this and other objects by the mechanism illustrated in the accompanying drawing in which Fig. 1 is a section of an instrument embodying the general principle of the invention; Fig. 2 is an elevation of the same instrument from the rear or from the side opposite the diaphragm; Fig. 3 is a section showing a slight modification of the instrument shown in Fig. 1; and Fig. 4 is an elevation of the instrument shown in Fig. 3.

In the several figures of the drawing numeral 1 designates the spool containing the actuating coil through which the non-helical ferreous armature 2 passes without any mechanical contact. U-shaped pole-pieces 3, 3 surround the spool 1 with their limbs approaching the armature on either side at its ends, and magnets 4, 4 contact with said pole-pieces. The armature 2 is held in proper position within the spool and between the pole-pieces by tension members, preferably wires 5, 5 which are stretched upon the bracket 6 and secured to the armature 2 by solder or other suitable means. The bracket 6 is secured to the magnets 4, 4.

In the mechanism shown in Figs. 1 and 2, the movement of the armature 2 is communicated to an acoustic element such as a diaphragm 7 by means of a lever arm 8 mounted upon the armature 2 and a flexible connecting link 9. The diaphragm 7 is supported by a spring 10 secured to the bracket 6. The tension of the wires or members 5, 5 is adjustable by means of the screw 11.

The structure shown in Figs. 3 and 4 is the same as that shown in Figs. 1 and 2 except that the lever arm 8 consists of a yoke passing over the polepiece 3 and connecting with both ends of the armature. This gives greater rigidity to the armature and lever arm.

In either structure it will be seen that in operation under the influence of telephonic currents in the coil the armature will be acted upon by equal and opposite forces at its opposite ends which will cause it to oscillate about a point at or near its center. This movement will be communicated to the diaphragm 7 by means of the lever arm 8 and flexible connecting link 9. The position of this connecting link is parallel to the tension members 5, 5 therefore in reacting upon the armature it will have no tendency to displace the armature up or down and the armature will operate in the same manner as if it were pivoted at the center. The armature has no fulcrum, but with this particular combination of forces the tension members are the equivalent of a fulcrum, serve the same purpose, and may be said to constitute a fulcrum at the center of the armature. In other words the armature has a virtual fulcrum at the center. This virtual fulcrum and the axis of oscillation of the armature lie substantially without the supporting means. While the connecting link 9 will have a transverse motion with the armature 2 it will also have a longitudinal component due to the lever arm 8 which will move the diaphragm 7. The mechanical advantage of the system as applied to the diaphragm is determined by the distance from the armature at which the connecting link 9 is connected to the lever arm 8.

As here disclosed the armature is operatively connected with a cone diaphragm of a loud speaker, but it is obvious that the invention can be used in other kinds of acoustic instruments such as inductive transmitters, inductive phonograph reproducers, or electrical phonograph recorders.

I claim:

1. A telephone receiver comprising an armature operatively connected with a diaphragm and surrounded by an actuating coil, tension members supporting said armature, and constituting a virtual fulcrum for said armature.

2. A telephone receiver comprising an armature operatively connected with a sound producing mechanism and surrounded by an actuating coil, tension members supporting said armature, and constituting a virtual fulcrum for said armature.

3. An acoustic instrument comprising an armature, an actuating coil surrounding said

armature, an acoustic element, means operatively connecting said armature with said acoustic element, and tension members supporting said armature and constituting a virtual fulcrum for said armature.

4. An acoustic instrument comprising an armature, an actuating coil surrounding said armature, an acoustic element, means operatively connecting said armature with said acoustic element, and tension members supporting said armature and constituting a virtual fulcrum for said armature within said coil.

5. An acoustic instrument comprising a non-helical ferreous armature, an acoustic element, means operatively connecting said armature with said acoustic element, and tension members supporting said armature and

constituting a virtual fulcrum for said armature.

6. An acoustic instrument comprising a non-helical ferreous armature, an acoustic element, means operatively connecting said armature with said acoustic element, supporting means disposed at either end of said armature and permitting said armature to oscillate about a point between its ends.

7. An acoustic instrument comprising an armature, an actuating coil surrounding said armature, an acoustic element, means operatively connecting said armature with said acoustic element, and supporting means wholly without said coil and supporting said armature and permitting said armature to oscillate about a point within said coil.

NATHANIEL BALDWIN.
